By Henry Ward Beecher

UNITED STATES PATENT OFFICE

JOHN GLOVER, OF CHICAGO, ILLINOIS

MOP

Application filed October 17, 1931. Serial No. 569,363.

This invention has to do with a mop and more particularly with an improved form of head and handle socket therefor.

Formerly, household mops designed to pass under furniture and other low objects have been of a flat type, and employed a handle socket angularly displaceable to the mop head. In each case heretofore, however, the handle mounting is above the mop head so that when the handle is lowered to a horizontal position the socket projects above the mop body at least to the amount of its diameter. In conventional mops on sale at the present time, most mops have handles which cannot be moved to an angle of zero degrees to the top surface of the mop head.

The principal object of the present invention is to provide a mop having all of the useful features of conventional floor mops, but adapted to permit the means for attaching the handle to the head to fall below the horizontal plane of the mop head.

Those familiar with the art of mop making have long realized the importance of producing a floor mop capable of reaching beneath objects having little floor clearance, and have brought forth mops intended to accomplish this feat, but these devices have met with little degree of success.

Another object of the present invention is to provide a simple and effective mop head manufacturable with a limited number of operations and from a single piece of sheet stock.

A further object of the present invention is to provide a mop head having a handle centrally mounted.

Objects, other than those just described, will be made apparent in the following description and appended claims.

Figures to be read conjointly with the description of the invention and having like reference characters designating similar parts comprise the one sheet of drawing included herewith and made a part of this specification, and in which:

Figure 1 is a top or plan view of the embodiment of the invention;

Figure 2 is a sectional view of the device taken on the line 2-2 of Figure 1; and

Figure 3 is a cross section along the line 3-3 of Figure 1.

The reference character 10 designates a generally heart shaped plate which comprises the mop head. Centrally located at the back edge of plate 10 is a rectangular cutaway section 11 bounded by sides 12 having shoulders 13 and an end 14. Coextensive with the perimeter of the mop head 10 and terminating at shoulders 13 is a narrow-flange 15 struck downwardly from the mop head, and providing several spaced apart lugs 16.

A strip of binding material 17, from which depends thrums 18, is drawn tautly against the periphery of flange 15 and secured thereto by means of rivets 19 anchored in lugs 16. Ends 20 of the binding strip 17 are directed neatly into section 11 of the head by means of additional rivets 19a located in shoulders 13. Such disposition of the ends 20 prevents the metallic shoulders 13 from striking and thus disfiguring objects of furniture.

With the stamping of base 10, a shallow channel 21 is beaded near the edge of said base. Small apertures 22 placed at intervals along the bottom of the bead 21 act as orifices through which oil placed in the channel 21 may flow to distribute uniformly over the thrums below.

A saddle strap 23 (Figure 3), providing a transverse arcuate bearing surface 24, is pressed downwardly from the center of plate 10. At either end of bearing 24 and in alignment therewith, complementary bearings 25 are stamped upward from the stock of plate 10.

A socket 26 for holding a mop handle 27 is assembled from a flat sheet of metal to have a receptacle 28 formed of curved and opposed side members. An extension 29 of the back wall of socket 28 is articulated at its end to form a loop 30 containing a bearing 31 and held in position by a rivet 32.

Socket 26 is introduced to the mop head 10 with the lower side of loop 30 seated in bearing 24 and with its side members projecting into slot 11. At this time a pintle

33 is driven from the lower side of mop head 10 into bearing 31 with the ends disposed in bearings 25. Strap 23, which is deformed during this operation, immediately retracts 5 to carry the pin 33 well up contiguous bearings 25, where longitudinal movement thereof is prevented by the strictured ends of said bearings. Thus, the socket and mop handle therefor are pivotally attached to the mop 10 head in a manner to adapt an angular combination therebetween permitting of the mop handle to occupy a horizontal plane beneath the horizontal plane of the top of the mop head 10 and allowing the mop to be pushed 15 by such handle into spaces of no greater clearance than required to accommodate the mop head itself.

I claim:

1. A mop comprising a plate having two 20 depressed sections, one countersunk in the front portion of the other, the material of the plate adjacent to the opposite sides of the front depressed section being raised, there being a slot extending from the rear edge of 25 the plate to the back bottom edge of said rear depressed section, a pin over said front depressed section and extending beneath said raised sections of material, and a socket pivotally anchored to said pin, the angular movement of said socket into a rearwardly horizontal position being limited only by the material of said rear depressed section.

2. A mop head comprising a plate having a slot extending inwardly from the rear edge 35 thereof, there being a depressed section in the material of said plate extending from the front of said slot, and a second depressed section countersunk in the front of the first named depressed section, a handle socket, 40 and means extending across said countersunk section for providing a pivotal anchorage for said socket, the first named depressed section and said slot receiving said socket incident to said socket being pivoted backwardly.

45 3. In a mop, a head comprising a plate having a seat for a socket, there being a section of said plate depressed to effect said seat and there being smaller and elevated sections in said plate at the opposite sides and 50 near the front of said depressed section thereby effecting apertures in said plate between the elevated and depressed sections, and a pin extending across said seat into said apertures, said socket being pivotally connected 55 to said pin, and said seat being of a depth to admit of said socket being disposed therein to lie therein in parallelism with the top surface of said plate and in substantial alignment therewith when moved about said pin.

60 4. A mop head comprising a flat plate having a slot extending from the edge thereof toward its center, there being in said plate at the end of said slot a downwardly displaced section to form a socket rest, the material 65 of the plate in the front opposed sides of

said rest being apertured, a pintle extending across said rest and having its ends disposed within said apertures, and a handle socket member connected to said pintle and adapted to be pivoted thereabout to be seated in said socket rest.

5. The mop described in claim 4, in which said handle socket member is of strap material extending about said pintle, the material of said socket being bent into a body adapted to be disposed within the slot and in parallelism with said plate.

6. A mop head comprising a flat plate having a depending flange to receive thrums, the thrums extending above the plate and being arranged around said plate except at its rear, there being a slot at the rear of said plate, a pintle, and a socket connected to said pintle, the material of said plate to the front of the slot being depressed to form two seats, one of said seats being countersunk in the front section of the other to receive said pintle, and the other of said seats forming a rest for said socket and defining its angular movement in one direction, the material of said socket having its slightest depth over said seat to permit of the top of said socket being moved into parallelism with the plane of said flat plate.
